N. O. THORP

WIRE STRETCHER

Filed June 5, 1926

FIG. 1.

FIG. 4.

FIG. 2.

FIG. 3.

FIG. 5.

Inventor

Noah O. Thorp.

By Watson E. Coleman
Attorney

UNITED STATES PATENT OFFICE.

NOAH O. THORP, OF CLEO, TEXAS.

WIRE STRETCHER.

Application filed June 5, 1926. Serial No. 113,883.

This invention relates to wire stretchers and more particularly to a device for stretching and holding fence wire while applying the same to a post.

5 An important object of the invention is to provide a device of this character so constructed that when the wire is properly stretched and ready for stapling to the post, the stretching device may be released with 10 the hands, so that the hands are free for the stapling operation and still hold the wire in its proper position.

15 A further object of the invention is to provide a device of this character which may be readily so constructed that it embodies all of the necessary accessories to the 20 stapling operation.

25 A still further object of the invention is to provide a device of this character which may be readily and cheaply produced, which will be durable and efficient in service and a general improvement in the art.

These and other objects I attain by the 25 construction shown in the accompanying drawing, wherein for the purpose of illustration is shown a preferred embodiment of my invention and wherein:—

Figure 1 is a plan view showing a wire 30 stretcher constructed in accordance with my invention positioned to stretch wire for attachment to a post;

Figure 2 is a section on the line 2—2 of Figure 1;

Figure 3 is a section on the line 3—3 of 35 Figure 1;

Figure 4 is a section on the line 4—4 of Figure 1;

Figure 5 is a section on the line 5—5 of Figure 1.

40 Referring now more particularly to the drawing, the numeral 10 generally designates a bar formed at one end to provide divergent nail claws 11 curving from one side face of the bar and the opposite end of this lever is formed as one jaw 12 of a wire 45 cutter and has pivoted thereto a lever 13, one end of which is formed as the second jaw 14 of the cutters and the opposite end of which provides a handle 15.

50 To the bar adjacent the first mentioned end thereof is secured a housing 16 which extends transversely of the lever and provides a guide opening 17 through which is directed a rack bar 18. Within the housing at the opposite face of the bar 18 from the rack teeth are disposed rollers 19 for

engagement with this face of the bar to reduce the friction of the bar in the guide. One end of the bar is provided with a head 20 to engage against one end of the housing 60 and limit the movement of the bar in one direction while the opposite end of the bar is formed as a cam face 21 having a reduced extension 22 upon which is pivoted a cam wire grip 23. This cam wire grip has at 65 its upper face a lug 24 which, when the wire grip is in the gripping position, overlies the upper surface of the rack bar 18 adjacent the cam and prevents the escape of a wire from between the cam 23 and cam 70 face 21. When the cam 23 is in the releasing position, this lug is spaced from the bar, so that the wire may be disengaged from between the cam face and cam by a movement 75 perpendicular to the bar. Rotatably mounted upon that side face of the bar 10 over which the rack bar extends is a gear 25 having a handle 26 secured thereto whereby it may be rotated. The teeth of this gear 80 engage with the teeth of the rack and provide means for longitudinally shifting the rack to tension the wire. When the wire is properly tensioned, it may be held in position by a pawl 27 which engages in the teeth of the gear.

In use of the device, the bar 10 is applied to one face of the post 28 to which the wire is to be attached and the wire grip 23 is engaged with the wire. At this time, the head 20 of the rack bar should engage against the 90 rack bar housing and the application of the wire should be made with the wire stretched to the greatest possible extent by the hand. The bar 10 is then employed as a lever to further stretch the wire and when the wire 95 has been stretched to the desired extent by the bar 10, the bar 10 is held against return movement by swinging a pivoted cant dog 29 engaged with the bar 10, as at 30, so that it engages with the post 28. The end 100 of this cant dog is provided with forked prongs 31 which engage the post at opposite sides of the wire being stretched, so that the holding pressure is applied in a line through the cant dog and tendency of the lever to 105 slip upon the post is prevented. The handle 26 is then employed to rotate the gear 25, shifting the rack bar to further tension the wire until the desired tension has been obtained. The rack bar is then held against movement by the pawl 27 and the operator 110 may then entirely release the device and em-

ploy both hands in the stapling operation.

It will, of course, be obvious that the construction hereinbefore set forth is obviously capable of a certain range of change and modification without materially departing from the spirit of the invention and I accordingly do not limit myself to such specific structure except as hereinafter claimed.

10 I claim:

1. In a wire stretcher, a main bar adapted at one end for engagement with a post, a housing secured to said bar adjacent said end and extending transversely of the main bar, a rack bar slidably directed through said housing and having at one end a wire grip, a gear pivoted to the main bar and meshing with the teeth of the rack bar, an arm secured to said gear whereby it may be rotated, means for maintaining the rack bar in adjusted positions and a cant dog pivoted to the main bar at a point beyond

the rack bar from said end of the main bar and adapted to engage with the post.

2. In a wire stretcher, a main bar adapted at one end for engagement with a post, a housing secured to said bar adjacent said end and extending transversely of the main bar, a rack bar slidably directed through said housing and having at one end a wire grip, a gear pivoted to the main bar and meshing with the teeth of the rack bar, an arm secured to said gear whereby it may be rotated, means for maintaining the rack bar in adjusted positions and a cant dog pivoted to the main bar at a point beyond the rack bar from said end of the main bar and adapted to engage with the post, the post engaging end of said cant dog being bifurcated to straddle the wire engaged by the grip of said rack bar.

In testimony whereof I hereunto affix my signature.

NOAH O. THORP.
